CIGARETTE SNUFFER

Herbert L. Williams, Ventura, Calif.

Application August 31, 1950, Serial No. 182,551

6 Claims. (Cl. 131—237)

1

This invention relates to a device for extinguishing lighted cigarettes and particularly to a type of such devices popularly called cigarette snuffers.

One of the objects of my invention is to produce a device of this type having means for automatically snuffing, that is, extinguishing the cigarette when the burning end of the cigarette is thrust into the device.

Another object of the invention is to construct the device so that it can readily be constructed of a few parts, one of which functions as a base having a chamber in which the snuffed out butts will be collected and which can readily be dumped from time to time. Further objects of the invention will appear hereinafter.

The invention consists in the novel parts and combinations of parts to be described hereinafter, all of which contribute to produce an efficient cigarette snuffer.

A preferred embodiment is described in the following specifications, while the broad scope of the invention is pointed out in the appended claims.

In the drawing:

Fig. 1 is substantially a vertical section through the snuffer, with a portion of the device shown in front elevation.

Fig. 2 is a horizontal section taken about on the line 2—2 of Fig. 1, further illustrating elements that co-operate to effect this snuffing operation.

Fig. 3 is an elevation of the upper end or receiver of the device as viewed from the right side of Fig. 1.

Fig. 4 is a top plan view of the device.

Fig. 5 is a horizontal cross section on line 5—5 of Fig. 6, but shows the parts as though the section has been rotated through ninety degrees about its axis.

Fig. 6 is a fragmentary side elevation showing a modified form.

Referring more particularly to the parts, the device comprises a casing 1 including a base portion or body 1a and a receiver neck 1b, preferably of substantially tubular form, and surmounted by a mouth or inlet 2 having an unobstructed opening 3 through which the cigarette butt may be introduced.

When so introduced the burning butt end of the cigarette impinges upon a movably supported stop means 4 that preferably includes two or more pivotally supported arms, or levers 4a. These arms 4a may operate as levers to actuate means for engaging a cigarette butt in such a way as to extinguish it. In the present instance that is effected by severing the lower end of the cigarette, so that the cut off end can fall into the collecting basin or tray 5 within the body 1a. The body 1a is hollow preferably of the shell form shown in Fig. 1 and is removably attached to the tubular neck 1b.

The receiver for the cigarettes includes a de-

2

pressible head 6 that is preferably of mushroom form with a tubular stem or inner sleeve 7 below that fits neatly into the open end of the neck 1b, and this sleeve is guided to slide up and down

5 in the neck 1b.

I prefer to use two snuffer blades 4b disposed diametrically opposite each other, and these blades are also preferably made integral with their stop arms or levers 4a. The blades 4b terminate in end portions 4c which are adapted to engage the lit end of a cigarette.

This enables these two parts to be made of a single blank of plate form which may be bent substantially to the shape shown in Fig. 1, so that each blade 4b overlies its stop plate 4a but is disposed in an inwardly and upwardly inclined position. And the upper ends or edges 8 of the blades 4b are spaced apart sufficiently to enable the cigarette butt to pass down between them 10 and impinge or rest against the stop plates 4a that are preferably curved slightly, with their convex faces uppermost.

In forming these plate members 4a and 4b, the blank from which they are formed is bent 25 to form a sleeve or eye 9 through which a pivot pin is placed; and the ends of this pin are held in small eyes 10 formed on the upper ends of two tongues 11, that are integral with the material of the neck 1b and extend upwardly from its 30 upper edge.

Just below the mushroom head 6, the sleeve 7 has two oppositely disposed openings 12 through which the snuffer members 4 extend, so that the tips of the plates 4a lie near each 35 other and below the opening 3.

When the lighted end of the cigarette is pushed down through the opening 3 it can pass between the edges 8 of the snuffer blades 4b that are spaced apart a distance about equal to the diameter of the opening 3.

The snuffer is preferably actuated by depressing the sleeve 7 against the force of the coiled spring 13 which is housed in the neck 1b and thrusting upwardly against the lower end of the sleeve 7. The upper edges of the openings 12, moving down against the snuffer blades 4b causes them to rotate in opposite directions, forcing them down so that their edges 8 cut off and snuff a cigarette butt that may be supported on the stop plates 4a.

In the position of rest of the parts the spring is fully extended and not in compression, so it requires very slight force to depress the head 6 to actuate the snuffer members.

55 The tips 4c of the plates 4a are preferably slightly out of line with each other in a vertical plane, so that they will not jam on each other when they are swung inwardly.

In order to prevent the cigarette butt from slipping sidewise in such a way as might possibly prevent it from engaging the snuffer members I prefer to provide two guides 16. As here illustrated they are in the form of rectangular plates

disposed in a vertical plane and located respectively adjacent to the paths of the side edges of the snuffer members 4. The ends of these guide plates 16 are bent laterally to form short arc-shaped flanges 17 that are soldered or otherwise secured to the inner face of the sleeve 7. (See Figs. 1 and 2.)

At the upper portion of the head 6 the wall is formed into a downwardly projecting flange as shown in Fig. 1, the downwardly and radially inclined arcuate portion of which operates as a guide to assist in centering the cigarette into opening 3.

Any suitable means such as bayonet slots may be used if desired, instead of the threads 18 for detachably securing the neck 1b to body 1a that functions as an ash tray. Since the sleeve assembly can be lifted out when desired, the collecting chamber 5 can readily be dumped by inverting the base and shaking it. Then the spring 13 and the sleeve and ashes will fall out. The sleeve assembly can then be readily replaced.

If a cigarette butt is too short to handle without danger of burning the user it can be put in the opening 3 with its lower end resting on the stop plates 4a; and the pressure of one's finger on the top of head 6 can operate the snuffers as described above.

In Figs. 5 and 6 I illustrate another embodiment of the invention in which I dispense with the pieces 16 that function to keep the cigarette butt moving straight down.

In this embodiment I form the sleeve 7 with a flat sided cross-section or throat by pressing its wall inwardly by means of dies at two diametrically opposite points to form two flat cheeks 7a (see Fig. 5); these cheeks 7a perform the same function as the inner faces of the guide pieces 16, and the sleeve wall between these flat cheeks has a cylindrical shape as indicated at 7b. At the upper portion of the cylindrical surface at these points the side openings 1c are formed. Fig. 5 shows the section as it would be looking upwardly, so the bulbous head 7d is in view.

This cigarette snuffer or extinguisher is preferably operated by placing the lighted end of a cigarette past the unobstructed opening 3 in the head 6, and pushing the cigarette down until its lower end rests on the stop plates or wings 4a below the blades or knives 4b. The smoker should then slide his fingers down the cigarette until they contact the upper side of the head 6. Then by pressing the head 6 downward the knives 4 will swing downwardly, and their edges 8 will cut off the lighted end portion of the cigarette. When the smoker releases the head 6 the severed burning butt end of the cigarette will have passed down through the lower end of the neck or sleeve 7 and will have dropped into the chamber 5. The remainder of the cigarette may then be thrown away or if it is sufficiently long may be lighted again for another smoke.

The knives 4b make a clean even cut across the cigarette so that the use of this snuffer or extinguisher eliminates unsightly mutilated cigarette butts lying in ash trays, or unextinguished butts that are frequently left to smolder there.

One downward movement of the head 6 suffices to snuff the butt end and deposit it in the chamber 5.

When this snuffer or extinguisher is used in an automobile being driven through a dangerous fire area it greatly reduces the danger from forest fires.

Many other embodiments of the invention may

be resorted to without departing from the spirit of the invention.

I claim as my invention:

1. In a cigarette snuffer, the combination of a casing with a chamber for receiving snuffed cigarette butts, a manually operable actuating member having an unobstructed opening adapted to receive the butt end of a cigarette, and guided to be moved bodily downward on said casing, stop means pivotally mounted on said casing between said opening and said chamber in a position to engage and stop said butt end when the same is passed through and beyond said inlet opening, and snuffer means movably supported on the casing and actuated by the downward movement of said actuating member when the same is moved downwardly by the operator's hand for snuffing the cigarette butt.

2. A snuffer according to claim 1, said snuffer including a plurality of blades spaced apart circumferentially about the axis of said inlet, and a connection between said actuating member and said blades for moving the blades downwardly and towards each other to effect the snuffing of the cigarette end.

3. A cigarette snuffer according to claim 1 including guides disposed at the sides of the snuffer members for preventing the lit end of the cigarette from moving laterally out of the path of the snuffer members.

4. A snuffer according to claim 3 in which the casing includes a tubular neck extending upwardly from the base for supporting the snuffer members, a sleeve adapted to telescope in the neck and guided to slide upward and downward therein, said sleeve having openings through which the snuffer members project inwardly, and a return spring for normally holding the sleeve and the snuffer members in their upwardly disposed position of rest.

5. In a cigarette snuffer, the combination of a casing having a substantially tubular neck, a sleeve guided to slide up and down in the neck and having an upper opening for the introduction of a cigarette, snuffer members below said opening pivotally supported on said neck including snuffer means adapted to move inwardly for engaging the ignited end of a cigarette to extinguish it, a return spring in the neck thrusting upwardly against the sleeve, said sleeve having means for engaging said snuffer members for actuating them and normally maintaining the snuffers in their upwardly disposed position of rest.

6. A cigarette snuffer according to claim 1 in which the casing includes an upwardly extending neck and a sleeve guided for movement down and up in the neck, said sleeve having openings through which the snuffer members project inwardly, said sleeve also having flattened side wall portions at the sides of the snuffer members for confining the cigarette butts against moving laterally when the snuffer members engage the cigarette butt.
